US00D438563S

(12) **United States Design Patent** (10) Patent No.: **US D438,563 S**
Webb et al. (45) Date of Patent: ** Mar. 6, 2001

(54) **TRANSPARENT CARD WITH AN OPACITY GRADIENT**

(75) Inventors: **Lisa Webb**, Darien, CT (US); **William J. Faenza, Jr.**, Manassas, VA (US); **Ellen Lasch**, New York; **Judy Vigiletti**, Croton, both of NY (US)

(73) Assignee: **American Express Travel Related Services Company, Inc.**, New York, NY (US)

(**) Term: **14 Years**

(21) Appl. No.: **29/110,194**

(22) Filed: **Sep. 1, 1999**

(51) LOC (7) Cl. **19-08**

(52) U.S. Cl. **D19/10; D19/9**

(58) Field of Search D14/435, 436, D14/437, 438, 479; D19/9, 10; 235/380-382.5, 441-443, 449, 454, 457, 469, 487-494; 283/72, 74, 75, 77, 78, 82-93, 107-114, 904

CLAIM

The ornamental design for a transparent card with an opacity gradient, as shown.

DESCRIPTION

FIG. 1 is a perspective view of a transparent card with an opacity gradient showing my new design;

FIG. 2 is a front view of the transparent card of FIG. 1;

FIG. 3 is a rear view of the transparent card of FIG. 1;

FIG. 4 is a right side elevational view thereof;

FIG. 5 is a front elevational view thereof; and,

FIG. 6 is a rear elevational view thereof.
